(57) **CLAIM**

The ornamental design for a leg support, as shown and described.

DESCRIPTION

FIG. 1 is a side perspective view of a first embodiment of a leg support, showing my new design in an environment in which the leg support is typically installed, such as on a medical support platform that supports a patient.

FIG. 2 is a side perspective view thereof.

FIG. 3 is an overhead view thereof.

FIG. 4 is an underside view thereof.

FIG. 5 is a front elevational view thereof.

FIG. 6 is a rear elevational view thereof.

FIG. 7 is side elevational view thereof.

FIG. 8 is a side perspective view of a second embodiment of a leg support, showing my new design.

FIG. 9 is an overhead view thereof.

FIG. 10 is an underside view thereof.

FIG. 11 is a front elevational view thereof.

FIG. 12 is a rear elevational view thereof; and,

FIG. 13 is a side elevational thereof.

The broken lines depict environmental subject matter and form no part of the claimed design.
